Geo. Stevens.
Attorney

UNITED STATES PATENT OFFICE

JOSEPH BERG, OF DULUTH, MINNESOTA

COLLAPSIBLE RECEPTACLE

Application filed May 10, 1930. Serial No. 451,359.

This invention relates to improvements in collapsible baskets, pails, or the like, and has special reference to a collapsible pail or basket particularly adapted for use by tourists, campers, or the like, and which may be carried in a minimum of space, which forms the principal object of the invention.

Another object is to provide such a collapsible article which will function in every respect similar to the ordinary non-collapsible one.

Other objects and advantages of the invention will appear in the following description thereof.

Referring now to the accompanying drawings, forming part of this application, and wherein like reference characters indicate like parts:

Figure 1 is a side elevation of the device frame and showing the flexible element thereof in section.

Figure 2 is a section of the manner in which the frame members are hingedly united.

The device in its broadest sense comprises a foldable wire frame structure having disposed therewithin a fluid holding or water-proofed fabric pail or bucket and which of course is foldable within and with the frame.

The frame structure comprises a pair of wire hoops 1 and 2, forming the top and bottom of the device, a locking hoop or ring 3 and the hingedly united spacing members 4. The spacing members 4 are of V and inverted-V shape, the apex of one being wound about the apex of the other and the free ends being wound about the top and bottom rings; so that they are, broadly speaking, hingedly united to each other and to the spaced rings.

The upper V-shaped portion of each spacing member is attached to the top ring 1 by the free ends of said portion being coiled one turn about the ring as at 5 and so that they may swing thereon. The apex of the upper portion is coiled twice about the apex of the lower portion, as at 6, and the axis of this coiled portion 6 is transverse the axis of the rings 1 and 2; the free ends of the lower portion being coiled one turn about the bottom

ring 2. Thus the two portions of the spacing

members are pivotally united and consequently may fold inwardly and thus collapse the basket or pail to such an extent that the top and bottom rings almost touch.

To hold the device in its uppermost rigid position I have provided the locking ring 3 which is slidable longitudinally between the free ends of the upper portions, and of course when this ring is down adjacent the coiled portions 6 the spacing members cannot move and a very rigid frame structure results. To insure that this locking ring stays down against the coiled portions 6, the wire forming the upper V-shaped portions is bent inwardly as at 7 forming a hump over which the ring 3 must be forced before it assumes its final locking position.

The bail or handle 8 of the device is attached to the top ring 1 by means of the free ends of a U-shaped piece of wire 11 being coiled about the ring 1 and within which the hooked ends of the handle may be removably placed.

Of course across the bottom there extends two or three diametrically disposed wires, 75 they being in the same plane with the bottom ring 2 and form the bottom of the basket.

The device thus far described may admirably be used for a shopping basket or the carrying of large or bulky articles.

However should it become desired to use the device as a water pail there is provided the round canvas water-proofed bag indicated at 9, it being of a size to just fit within the wire frame structure, but the top of which is designed to fold over the top of said structure as indicated at 10. In applying the bag the handle is removed, the bag inserted, the wires 11 extending up through a pair of slots in the bag suitably placed, and the handle then applied; the handle thus acting to hold the bag securely in position.

From the foregoing it is apparent that I have described a very practical and efficient collapsible basket or pail and one that may be used for all ordinary purposes.

Having thus described my invention, what I claim and desire to secure by Letters Patent, is:

1. A collapsible device of the class de- 100

scribed including spaced rings, spacing members comprising V and inverted V-shaped portions pivotally united at their apexes to each other and at their free ends to the rings, 5 and an intermediate locking ring operable within the uppermost V-shaped members, and means for temporarily holding said ring in the apexes of said members when in locked position, said means including opposed kinks 10 within the wire of which said V-portions are formed.

2. A collapsible device of the class described including spaced wire rings, wire spacing members pivotally attached to the 15 rings and also to each other and having kinked portions therein, a slidably operable locking ring for holding the spacing rings rigid by passing said kinked portions, and a bag removably positioned within said device.

20 In testimony whereof I affix my signature.

JOSEPH BERG.
